UNITED STATES PATENT OFFICE.

WILLIAM W. KENNEY AND JOHN W. FOGLER, OF NEW LONDON,
CONNECTICUT.

UMBRELLA-RUNNER.

SPECIFICATION forming part of Letters Patent No. 707,237, dated August 19, 1902.

Application filed October 3, 1901. Serial No. 77,483. (No model.)

To all whom it may concern:

Be it known that we, WILLIAM W. KENNEY and JOHN W. FOGLER, citizens of the United States, residing at New London, in the county 5 of New London and State of Connecticut, have invented certain new and useful Improvements in Umbrella-Joints, of which the following is a full, clear, and exact description.

10 This invention has for its immediate object the improvement of the means provided in an umbrella for hinging the stretchers and ribs to the so-called "runner" and "spider," our chief aim being to provide hinging devices 15 that may be cheaply produced and quickly assembled or repaired.

The drawings annexed hereto illustrate our invention, Figure 1 being an elevation of an umbrella-stick with a single rib and stretcher 20 secured thereto by our improved means. Fig. 2 is an enlarged upper end view of the runner with portions of several stretchers radiating therefrom. Fig. 3 is a side view of said runner; and Fig. 4 is a plan view of the same 25 with the retaining-washer *g* partly broken away to disclose the manner of inserting the ball ends of the stretchers or ribs, as the case may be. Fig. 5 is a view of the sheet-metal blank from which the said runner is formed.

30 Fig. 6 is a longitudinal central sectional view of said runner and retaining-washer further enlarged, and in Fig. 7 we have shown said washer detached. Fig. 2 also serves as a lower end view of the spider, to which the rib 35 ends are hinged, inasmuch as the said spider *b* and runner are substantially alike in construction, differing only in length and in the fact that the spider is fixedly secured to the umbrella-stick.

40 In the drawings the letter *a* denotes the said stick; *b*, the fixed spider; *c*, the runner; *d*, the rib, and *e* the stretcher. The inner ends of the ribs and stretchers are formed with ball terminations *d'* and *e'*, respectively. The 45 ribs and stretchers are hinged together at *f* in the usual or any other practical manner. Inasmuch as the runner and spider are essentially alike we shall describe in detail only the runner. Said runner is formed from a 50 sheet-metal blank and rolled up into approxi-

mately the form shown in Fig. 5, the projecting portions *c'* being bent outward and then back upon the barrel of the runner, as is best seen in Fig. 6, to form sockets of suitable size to receive the ball ends *e'* of the stretchers, 55 and in order to facilitate the entrance of the balls the extreme ends of the projections *c'* are cut away or notched on opposite sides, as at *c''*. After the several ball ends of the stretchers have been seated in the described 60 sockets a washer *g* is slipped upon the barrel of the runner and moved into close engagement with the turned-in ends *c'*, and in order to lock the washer firmly to the runner certain of the projections on the runner-blank 65 are extended, as at *c''*, said locking projections being so bent prior to the assembling of the runner and washer that they (the projections *c''*) will lie close to the runner and allow the washer to slip over them. Preferably the 70 washer is notched, as at *g'* so that it may slip freely over the projections *c''*, and after the washer has been forced to its home position the ends *c''* are bent outward, (see Figs. 6 and 7,) thus locking the washer securely to the 75 runner. The washer then serves to protect the several turned-in ends *c'* and also to prevent the accidental escape of the ball ends of the stretchers through the notches *c''*. The hinge-joints thus provided permit the free 80 movement of the stretchers and ribs under all conditions. Said joints may be cheaply produced, and they are particularly convenient whenever it becomes desirable or necessary to remove an old rib or stretcher and insert 85 a new one.

Having thus described our invention, we claim as new and desire to secure by Letters Patent—

1. In an umbrella, in combination with ball-end ribs, a tube with split ends turned back to form sockets for said ribs, a retaining-washer mounted upon said tube, and means consisting of projections *c''*, as herein set forth, for locking the said washer in its operative position. 90

2. In an umbrella, the combination of the ribs, the tubes having the long and short split ends forming sockets for the ribs, and the washers having recesses to receive the ends 95 100

of the long ends, said ends locking the washers in place.

3. In an umbrella, the combination of the ribs, the tubes having the long and short split 5 ends turned under to form sockets for said ribs, and said long ends having their terminals turned under, and a washer secured by said long ends.

Signed at New London, Connecticut, this 23d day of September, 1901.

WILLIAM W. KENNEY.
JOHN W. FOGLER.
